UNITED STATES PATENT OFFICE

DONALD LANSPA AND WILLIAM M. LANSPA, OF OMAHA, NEBRASKA

SEAT COVER

Application filed April 30, 1931. Serial No. 534,107.

This invention relates to sanitary covers, designed primarily for use in connection with toilet seats of public lavatories.

An important object of the invention is to provide a device of this character including a web or strip formed of tissue paper, or other suitable flexible material, the web or strip being supported in such a manner that it may be moved over the seat proper, to completely cover the seat, for the protection of the user.

A further object of the invention is the provision of mechanical means for feeding the web or strip over the seat, novel means being provided for stopping the strip, after a predetermined length of the cover has been unwound from the supply roll, to properly cover the seat.

A still further object of the invention is to provide a device of this character which may be readily and easily positioned adjacent to a toilet seat, eliminating the necessity of making changes in the usual seat construction, to position the device.

With the foregoing and other objects in view, which will appear as the description proceeds, the invention resides in the combination and arrangements of parts and in the details of construction hereinafter described and claimed, it being understood that changes in the precise embodiment of the invention herein disclosed, may be made within the scope of what is claimed, without departing from the spirit of the invention.

Figure 1 is a plan view of a seat equipped with a cover constructed in accordance with the invention.

Figure 2 is a sectional view taken on line 2-2 of Figure 1.

Figure 3 is a sectional view taken on line 3-3 of Figure 1.

Figure 4 is a sectional view taken on line 4-4 of Figure 2.

Figure 5 is a sectional detail view showing one of the roll supports.

Figure 6 is a sectional view taken on line 6-6 of Figure 2.

Referring to the drawings in detail, the reference character 5 designates the usual

bowl which is supplied with a seat 6. The device comprises a rectangular frame indicated generally by the reference character 7, the frame being of a construction to be fitted adjacent to a bowl, without the necessity of removing the bowl or fixtures thereof.

At each side of the frame 7, are posts 8 disposed at the front and rear of the frame 7, and arranged in pairs at opposite sides of the frame. Slots are formed in the posts 8 near the upper ends thereof, which slots accommodate the shafts of the guide rolls 9, there being provided springs 10 within the posts, to urge the shafts of the rolls upwardly and yieldingly support the rolls 9. The reference character 11 designates the supply roll on which the web or strip is wound, and from which the web or strip is removed, during the operation of the device.

The strip is indicated by the reference character 12, and is formed preferably of tissue paper or other suitable material.

At the opposite side of the frame, is a feed roll 13 which has its outer surface covered with a cushioning material such as rubber or the like to grip the strip or web to feed the strip or web through the device.

The shaft of the feed roll 13 is indicated by the reference character 14, and extends into the frame 15 in which the gearing, employed in operating the feed roll, is mounted. The gearing includes a pinion 16, that is mounted on the shaft 17 of the motor 18, the motor 18 being in circuit with a suitable source of electric supply not shown.

Meshing with the pinion 16, is a gear 19 mounted on the shaft 14 of the feed roll, which shaft also carries the pinion 20 that meshes with the gear 21 which is secured to the shaft 22.

A wheel 23 is also mounted on the shaft 22 and has a notch 24 into which the right angled extremity of the spring arm 25 moves, the spring arm being secured to the gearing frame 15, at 26.

This arm 25 provides a support for the contact arm 27 to which the wire 28 of the

electric circuit, is secured. Disposed directly under the contact arm 27, is a contact member 29 to which the wire 30 forming the other wire of the electric circuit, is connected. These wires 28 and 30 connect with the motor 18 in such a way that when the circuit between the contact arm 27 and contact member 29 is completed, the motor will be thrown into operation.

10 A coiled spring 31 is mounted under the spring arm 25 and acts to normally urge the arm 25 and contact arm 27, upwardly. Pivotaly mounted on the frame 15 is a controlling lever 32 which has its forward 15 end disposed in a position to engage the spring arm 25 when the rear end of the lever is raised, the rear end of the lever being disposed in a position for easy access by the operator.

20 Thus it will be seen that due to this construction the operator, by moving the rear end of the lever upwardly, will force the spring arm 25 downwardly and out of contact with the wall of the notch 24, at the 25 same time completing the circuit to the motor, through the contact arm 27 and contact member 29.

It follows that the right angled end of 30 the spring arm 25 moving over the peripheral flange of the wheel 23, will hold the contact arm 27 into engagement with the contact member 29 to the end that the motor will continue to operate until the pinion 21 has made one complete revolution.

35 As the right angled end of the spring arm 25 snaps into the notch 24, the contact arm 27 moves away from the contact member 29, breaking the circuit to the motor, stopping the motor and feed roll 13. With 40 this movement, the strip or web is fed to a position to cover the seat with a fresh covering, the portion of the strip or web fed through the machine, being torn off, by the operator.

45 Associated with the feed roll 13, is a pressure roll 33 that is mounted in the tubular bearings 34, and held into engagement with the feed roll 13, by means of the coiled springs 35, which are tensioned by the set 50 screws 36.

It might be further stated that the supply roll 11 is held in slots providing bearings, the slots being formed in the posts 8, at one side of the frame, so that the supply roll 55 may be readily and easily removed and replaced when the strip or web carried thereby becomes exhausted.

A coiled spring 37 is mounted on the shaft of the supply roll, and bears against the 60 post 8 adjacent thereto, to hold the supply roll steadily and to prevent over-running of the supply roll, when the device is operated.

In view of the foregoing detailed description, a further detailed description as to the

operation of the device is believed to be unnecessary.

We claim:

1. The combination with a closet bowl and seat thereof of a protecting member 70 comprising a frame positioned over the bowl and seat, rolls mounted on the frame, a protecting strip carried by one of the rolls, said strip adapted to pass over the seat, an electric motor, gearing for transmitting movement of the motor to one of the rolls, a switch, wires providing a circuit between the switch and motor, a wheel rotated with the motor and having a notch in its periphery, said switch including an arm having a right angled end engaging the edge of the wheel, and adapted to move into the notch to operate the switch to break the circuit, and manually controlled means for operating the switch to complete the circuit. 75

2. The combination with a closet bowl and seat thereof, of a protecting member comprising a protecting strip supporting roll, a feed roll over which the strip moves, a shaft on which the feed roll is mounted, an electric motor for operating the feed roll, wires providing a circuit to the motor, a switch for controlling the circuit to the motor, said switch including a movable contact arm having a right angled end, a wheel 90 mounted on the feed roll shaft, said wheel having a notch, the right angled end of the contact arm engaging the periphery of the wheel and adapted to move into the notch to break the circuit to the motor, and means 95 for moving the contact arm to complete the circuit to the motor. 100

In testimony that we claim the foregoing as our own, we have hereto affixed our signatures.

DONALD LANSPA.
WILLIAM M. LANSPA.
